UNITED STATES PATENT OFFICE

127,348

DESIGN FOR A LABEL BLANK

Lawrence J. Gayda, Pittsburgh, Pa.

Application October 2, 1939, Serial No. 87,471

Term of patent 14 years

To all whom it may concern:

Be it known that I, Lawrence J. Gayda, a citizen of the United States, residing at Pittsburgh, in the county of Allegheny and State of Pennsylvania, have invented a new, original, and ornamental Design for a Label Blank, of which the following is a specification, reference being had to the accompanying drawing, forming part thereof.

Figure 1 is a plan view of a label blank showing my new design; and Figure 2 is an enlarged view of a portion of the label blank, the same being shaded to show contrasting color. The label blank has no appreciable thickness.

I claim:

The ornamental design for a label blank, substantially as shown and described.

LAWRENCE J. GAYDA.
